(57) CLAIM

The ornamental design for a card or photograph stand formed from a baseball bat, as shown and described.

DESCRIPTION

FIG. 1 is a perspective view of an embodiment of a stand for holding a card or photograph, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof.

The broken lines shown are included for the purpose of illustrating portions of the stand that form no part of the claimed design.

1 Claim, 7 Drawing Sheets
